LOOSE LEAF BINDER

Arthur W. McClure, Syracuse, N. Y., assignor to
McMillan Book Company, Syracuse, N. Y., a
corporation of New York

Application April 19, 1934, Serial No. 721,320

2 Claims. (Cl. 129—24)

This invention relates to improvements in a loose leaf binder in which straight leaf-impaling posts are releasably secured at both ends to a respective side of the binder.

5 The main object of the invention is to produce a loose leaf binder of the above mentioned class with improved means for automatically securing the leaf-impaling posts in the binder, as the binder is being closed.

10 A more specific object of the invention resides in providing a loose leaf binder with simply constructed means set into operation by the closing of a cover, for automatically and accurately alining the ends of the impaling posts with the post retaining means, whereby the retaining means may readily move into holding engagement with the posts.

In carrying out the above mentioned objects, I have utilized a loose leaf binder of well known 20 construction and which comprises a plurality of straight leaf-impaling posts and post retaining means, including a pair of housings secured one at a respective side of the binder, said housings having alined apertures in the walls thereof for 25 receiving the ends of the posts therethrough. A pintle slide is mounted in each housing for releasably engaging the respective ends of the posts to secure the posts to the housing and, therefore, to the binder.

30 Further, I have provided such a loose leaf binder with means adapted as the back and cover members move to the closed position, to first automatically effect the alinement of the loose or free ends of the leaf-impaling posts with respective openings in the adjacent pintle slide housing, and then to cause said ends of the posts to enter the openings and aline with the pintles of the slide, after which the pintle slide is automatically caused to operatively engage the posts for securing said posts to the housing.

Other objects and advantages relate to the details of the structure, and to the form and relation of the parts thereof, all as will more fully appear from the following description taken in connection with the accompanying drawings, in which:

Figure 1 is a perspective view of a loose leaf binder embodying the various features of this invention.

50 Figure 2 is an enlarged transverse sectional view through the back portion of the binder taken substantially on line 2—2, Figure 1.

Figure 3 is a longitudinal sectional view taken on line 3—3, Figure 2, and illustrating the central portion of the binder broken away.

Figure 4 is a detail longitudinal sectional view taken substantially in the plane of the line 4—4, Figure 2.

Figure 5 is a fragmentary perspective view of the pintle slide with portions thereof broken away and illustrating the latch member for releasably maintaining the pintle slide in the inoperative position.

Figure 6 is a detail transverse sectional view taken on line 6—6, Figure 4.

The loose leaf binder as illustrated in the drawings comprises primarily a back member 1, two cover members 2 and 3, and a pair of leaf-impaling post retaining members 4, positioned one at either longitudinal side of the back member adjacent a respective cover. The covers 2 and 3 in this instance, are pivotally connected to the back member. The back member 1 may be constructed in any well known manner and in this instance, is made concavo-convex in cross section, while the means for pivotally securing the covers 2 and 3 to the back member consists of a hinge plate 5, which is formed concavo-convex in cross section and is secured to the concave or inner side of the back member by any suitable means such as rivets 6, or their equivalent. The hinge plate 5 has each longitudinal edge thereof extended a short distance beyond the corresponding edge of the back member 1 and formed with a plurality of longitudinally spaced hinge eyelets 7.

The covers 2 and 3 are constructed preferably from cardboard, or similar material, in the conventional manner and in this instance, each cover has a hinge strap 8 positioned therein intermediate the inner and outer surfaces at the inner longitudinal edge thereof and which may be secured to the cover in any suitable manner as by rivets 9. The hinge straps 8 are secured to the respective ends of the hinge plate 5 by means of 30 pintle rods 10.

The post retaining members 4 as hereinbefore stated are positioned adjacent a respective longitudinal side of the back member and are arranged, when the covers are in the closed position, to lie just inside of the inner hinged edge of a corresponding cover. These retaining members are substantially identical in construction, so that a description of one will answer for a comprehensive understanding of them both.

Each of the retaining members 4 consists of a tubular housing 12 formed in this instance of sheet metal bent substantially U-shape to form a chamber 13 with the outer portion of the legs thereof extended inwardly in superposed relation 55

adjacent the inner face of the hinge plate 5, and are secured to each other and to the plate 5 by any suitable means, as by spot welding. The housings 12 have portions of the inner edges 5 thereof cut away to form aligned longitudinally spaced openings 14, each adapted to receive there-through an end of a respective post 15.

The posts 15 in this instance are rectangular in cross section and have each end thereof provided with an opening 16 extending transversely therethrough. These openings are adapted, when the posts are in the leaf holding position with the ends thereof positioned in a respective opening 14 of the housing, to register with the 10 corresponding chamber 13 of the housing and adapted to receive a respective pintle 17 provided on a pintle slide 18 mounted in each housing 12.

The pintle slide 18 in this instance, is a relatively long thin bar provided with recesses 19 in 20 the longitudinal edge thereof adjacent the openings 16, and has pintles 17 secured thereto to project into respective openings 19 and adapted, when the slide is in its innermost position, to extend across corresponding openings 14 of the 25 housing for engaging respective posts 15.

The slide 18 is normally urged inwardly to its innermost position with the pintles extending across the openings 16 by means of a coil spring 20, which has one end thereof secured to the 30 pintle slide and the other end connected with the housing 12, as shown in Figure 4. The slide 18 may be manually moved outwardly against the action of the spring 20 by any suitable means such as a finger piece or nob 21 secured to the 35 outer end of an extension 22 connected with one end of the slide 18, and which projects outwardly through the chamber 13. The finger piece 21 is so mounted on the extension 22 that the slide will be maintained in its innermost position 40 against the action of the spring 20 by the engagement thereof with the adjacent end of the housing 12, as illustrated in Figure 4.

Means is also provided for releasably maintaining the pintle slide 18 in its outermost inoperative position with the pintles 17 positioned 45 adjacent one side of the corresponding openings 14 against the action of the spring 20. This holding means consists, in this instance, of a latch 24 positioned in the chamber 13 near the 50 inner end of the pintle slide 18. The latch 24 is, as shown in Figure 4, pivotally connected at one end by a pin 25 to the housing 12. The latch 24 extends inwardly from the pivot 25 and has the inner end thereof adapted to move into the 55 path of movement of the pintle slide and engage the inner end thereof, when the said slide is in its outermost or inoperative position, for holding the slide in said inoperative position against the action of the spring 20. The inner end of the 60 latch 24 is normally urged toward the outer or rounded wall of the chamber 13 into the path of movement of the slide 18 by a coil spring 26 mounted in the recess 27, provided in the latch 24 intermediate the pivot 25 and the inner end 65 thereof, said spring having one end engaging the inner side wall of said chamber. The inner end of the latch 24 is relatively narrow in cross section and is adapted as illustrated in Figure 4, when the pintle slide 18 is in its innermost oper- 70 ative position, to extend along the inner edge of the slide between the said slide and the inner edge of the chamber 13.

In order that the latch 24 may be moved inwardly against the action of the spring 26 out of 75 the path of movement of the slide 18, I have

provided said latch with an outwardly projecting pin 29 which extends outwardly through a suitable aperture provided in the wall of the housing 12. This pin is adapted when the latch is in its operative position in holding engagement with the slide 18 to extend outwardly beyond the inner face of the housing 12 in the path of movement of the inner adjacent longitudinal edge of a cover 2 or 3 so that when the cover is moved to the closed position, the pin or member 29 will be engaged by the inner edge of the cover and moved inwardly thereby sufficiently to bring the inner end of the latch 24 out of holding engagement with the slide 18.

In order that the covers may efficaciously effect 15 the release of the latch 24, I have provided each cover with a reinforcing plate 30 which, in this instance, is L-shaped in cross section. Each plate has one leg thereof positioned adjacent the inner face of the respective cover while the other 20 or shorter leg 30' of the plate extends outwardly along the inner longitudinal edge of the cover as illustrated in Figures 2 and 6. The plates 30 may be secured to the respective cover in any suitable manner as by the rivets 9. These reinforcing 25 plates 30 extend longitudinally of the covers from within a short distance of one end to within a short distance of the other end, and are adapted, when the covers are being moved to the closed 30 position, to engage the adjacent ends of the posts 15 and move said posts into the corresponding openings 14 of the housing 12, and bring the openings 16 of the posts into alignment with the pintles 17.

It will now be observed that when one end 35 of the posts 15 is released by movement of the corresponding pintles 17 out of engagement therewith, the back member 1 and the cover connected therewith adjacent the released end of the posts, may swing outwardly about the pintle 40 hinge 10 at the opposite side of the binder away from the posts and leaves mounted on said posts. These leaves as 33 are mounted on the posts 15 45 in the conventional manner and for this purpose they are provided with the customary openings arranged in longitudinal spaced relation along one edge for receiving the posts there-through.

When the posts are connected at only one end 50 to the back member through the medium of the retaining member 4, the posts are maintained in their upright position by the leaves 33. Therefore due to the ease in which the leaves may move relative to each other, and assume an askew 55 position, the free ends of the posts very often become moved out of alignment so that when the detached retaining member is brought forwardly, as the back 1 is moved to the upright position, the free ends of the posts will be out of alignment with the openings 14 in the housing 12. It is, therefore, desirous and quite necessary when 60 automatically securing the posts in the binder, that some means be provided for again bringing the free ends of the posts into position to readily 65 enter the housing openings as the binder is being closed. For this purpose, I have provided the back member 1 with an alining means which 70 consists of an abutting plate 35 secured at the inner concave side of a hinge plate 5 in spaced relation thereto by means of three shouldered studs 36. These studs are secured to the back member by means of respective supporting strips 75 75 preferably composed of metal and which have the ends thereof secured by spot welding, or other

means, to the adjacent portion of the legs of the housings 12.

The abutting plate 35 is rectangular in plan view and extends longitudinally of the back member between the retaining housings 12 in such relation to said housings that when the posts are secured at both ends to the housings 12, the inner edge of the leaves 33 mounted on the posts will abut against the abutting plate 35. Furthermore, the plate 35 is provided at each end with outwardly projecting portions which extend at substantially right angles to said plate across the adjacent side of the leaves 33. These portions 39 are spaced apart a distance substantially equal 15 to the width of said leaves to form guide members adapted to engage the sides of the leaves adjacent said inner edges and each guide portion has the outer free side thereof bent outwardly as at 39' to enable the ready engagement thereof with 20 the leaves.

It may now be readily understood that when the binder is in the open position with one end of the posts released, the sides of the leaves will first be engaged by the guide members 39, as the back member 1 is swung forwardly about the axis of the pindle rod 10 at the attached side of the binder toward the leaves and thereby bring the sides of the leaves into alinement with each other. As the back approaches the normal upright position, the 25 rear edge of the leaves will be engaged by the abutting plate 35 and be alined thereby, with the result that as the leaves are thus brought into symmetrical relation one with another, the posts 15 will be moved thereby into such a position that 30 the free ends thereof will be in alinement with the openings 14 in the housing 12, as said housing approaches the free ends of the posts.

As the back member 1 approaches its normal upright position, the swinging of the cover adjacent the free ends of the posts about the pindle 40 10 from the open to the closed position will cause the inner longitudinal edge of the cover, or more specifically, the leg 30' of the reinforcing plate 30, to engage the upper or free ends of the posts, as 45 illustrated by broken lines in Figure 2, and force said ends of the posts into the respective openings 14 of the housing 12 to bring the openings 16 of the posts into alinement with the pintles 17. As the cover 2 approaches the closed position, the 50 pin 29 of the latch 24 will be engaged by the leg 30' of the plate 30 and automatically move the latch out of holding engagement with the pindle 55 slide 18 and permit said slide to be moved inwardly by the spring 20 so that the pintles 17 will come into holding engagement with the free ends of the posts 15 and secure said posts to the housing 12 in the leaf holding position.

Although I have shown and particularly described the preferred embodiment of my invention, I do not wish to be limited to the exact construction shown as various changes both in the

form and relation of the parts thereof may readily be made without departing from the spirit of this invention as set forth in the appended claims.

I claim:

1. In a loose leaf binder, a binder covering comprising a back member and a pair of covers hinged with respect to the back member, a plurality of impaling posts for retaining a quantity of paper, said posts being connected at one end to the binder covering, means for releasably securing the other or free end of the posts to the binder covering including a housing secured to the binder covering having openings for receiving the free ends of the posts, a slide in the housing movable into and out of holding engagement with the posts, means secured to the back member and engageable with the rear and side edges of the sheets of paper as the back and corresponding cover are being moved toward a position to reassemble the binder, said means serving to straighten up the stack of paper and thereby bring the posts into approximate alinement, means secured to the binder covering for moving the posts into the openings in said housing as one cover is moved toward a closed position, and means automatically set into operation when the cover is closed for bringing the slide into operative holding engagement with the posts. 20

2. In a loose leaf binder, a binder covering comprising a back member, a pair of hinges secured to the longitudinal edges of the back member and a pair of covers secured to said hinges, a plurality of impaling posts for retaining a quantity of paper, said posts being connected at the same ends to the binder covering, a plate secured to the inner side 35 of the back member and having portions thereof extending perpendicular to the back member and adapted to engage the side edges of the stack of paper, a post aligning member secured to the binder covering, a housing carried by the binder 40 covering having openings therein for the reception of the other ends of the posts, a slide mounted in the housing having pintles for engaging said other ends of the posts, said slide being manually movable to disengage the pintles from the ends 45 of the posts, spring means for normally urging the said slide in a direction such that the pintles engage said posts, retaining means for holding said slide so that the pintles are retained out of post 50 engaging position against the action of said spring, and means for automatically tripping said retaining means when the cover is thrown to a closed position during assembly of the binder to enable the spring to move the slide and pintles 55 into post engaging position, said plate and said post aligning member during the assembly of the binder co-operating to straighten up the sheets of paper and the posts to enable such automatic operation.

ARTHUR W. McCLURE. 60
